VALVE

Karl MacDonald, Wellsville, N. Y., assignor to
Worthington Pump and Machinery Corporation,
Harrison, N. J., a corporation of Delaware

Application October 5, 1945, Serial No. 620,480

10 Claims. (Cl. 251—49)

1

This invention relates to valves, and more particularly to hand operated nozzle control valves used on steam turbines to regulate the effective nozzle area of a steam turbine.

These valves which are manually operated are employed to control the flow of operating steam to nozzle groups of a steam turbine to obtain overload with rated steam conditions, returned overload with the reduced steam pressure, economical part load operation, etc. These valves, extending into and through the steam inlet ring of a steam turbine, are subjected to the temperature of the steam which causes expansion of certain valve parts, especially the valve stem which is contacted by the steam flowing to the turbine nozzles. The direct contact of the steam with the valve stem causes a greater degree of expansion of the stem than of the parts of the valve which are exterior of the steam ring, resulting in a binding of the valve stem to such a degree that a wrench is required to operate the valve.

It is an object of the present invention to provide a valve structure for the above described and analogous uses wherein the valve or parts thereof are subjected to high temperatures and uneven expansion, which valve embodies means to prevent binding of the valve parts upon expansion, and also means to dissipate heat from the valve parts so that the valve may at all times be operated by hand without the use of leverage tools.

With these and other objects in view, as may appear from the accompanying specification, the invention consists of various features of construction and combination of parts, which will be first described in connection with the accompanying drawings, showing a valve of a preferred form embodying the invention, and the features forming the invention will be specifically pointed out in the claims.

In the drawings:

Figure 1 is a fragmentary view in section of a part of a steam turbine showing the location of the improved valves.

Figure 2 is a vertical section through the improved valve.

Figure 3 is a cross section on the line 3—3 of Figure 2.

Figure 4 is a longitudinal section through a modified form of the valve.

Figure 5 is a cross section taken on the line 4—4 of Figure 4.

Figure 6 is a longitudinal section through a further modified form of the valve structure.

Referring more particularly to the drawings,

2

the steam inlet nozzles 1 of a steam turbine which deliver the steam to the blades 2 of the turbine are, as shown in Figure 1 of the drawings, isolated in groups to receive and project the steam by the various partitions 3 in the steam inlet ring 4 of the turbine into which steam flows from the inlet 5 under control of the inlet valve 6. The partitions 3 have steam inlet openings 7 therein through which steam from the steam ring 4 flows to the nozzles 1 in the group isolated by the respective partitions, and the valve of the present invention constitutes the hand operated valve structure 10 which is carried by the casing 8 of the turbine and controls the flow of steam through the ports 7.

The preferred form of the valve structure shown in Figures 2 and 3 comprises valve head 11 which seats against a valve seat formed on the removable valve seat ring 12 to cut off the flow of steam from the steam ring through the partition 3. The valve head 11 is shown as removably carried by a valve stem 13 through the medium of a removable connecting ring 14 and a flanged head 15 formed on the end of the valve stem 13. The valve stem 13 extends through the packing 16 carried by the valve attaching body 17 and has a threaded portion 18 thereon near its outermost end which is threadably engaged in the threaded bore 19 formed in the sleeve-like extension 20 of the bonnet or packing follower 21. The bonnet or packing follower 21 which is in the form of a flat disc having the sleeve 20 formed at one side thereof, and the packing engaging extension 22 formed at the other side is attached to the valve attaching body by means of bolts 23 which also serve to attach the body 17 to the turbine casing 8. The packing follower 21 has flat surface engagement with the valve attaching body 17, and it has an annular recess 24 cut in its inner side which reduces the thickness of a part of the follower 21 to provide a spring-like portion to permit yielding of the inner central portion of the follower under stress relative to the outer rim portion, which outer rim portion is bolted to the turbine casing 8 so as to accommodate expansion of the valve stem 13 when it is subjected to the high temperature of steam flowing to the nozzles 1 through the steam ring 4.

It is understood, of course, that the bonnet 21 is constructed of metal which has a sufficient degree of elasticity to permit such spring-like or yieldable movement. The bonnet 21 is provided with a plurality of vent openings 25 which vent the chamber formed by the cut-away portion 24

of the bonnet. The sleeve-like extension 20 has a plurality of longitudinally spaced radiating fins 26 formed thereon to dissipate heat for further co-operation with the yielding movement of the central portion of the bonnet body to prevent the threads 18 of the valve stem 13 from becoming wedged or sticking in the threads of the threaded bore 19 of the sleeve-like extension 20 upon expansion of the valve stem.

It will be noted that the sleeve-like extension 20, and, consequently, the threaded portion of the stem 13 are positioned beyond the valve attaching body 17 so that they are practically located as far as they may possibly be from the point of contact with steam with the valve stem, and also so that the sleeve-like extension 20 being relatively thin in proportion to the portion of the body 17 which extends into the steam ring 4 and being completely surrounded by air will dissipate heat transmitted thereto from the valve stem.

The packing follower 21 has a second chamber 28 formed therein which extends about a part of the threaded portion of the stem 13, and this chamber is vented to atmosphere by a port 29.

The valve stem 13 may have a hand wheel 30 or any other suitable means thereon to facilitate its manual operation.

A modified form of the valve structure is shown in Figures 4 and 5 of the drawings, and this modified form of valve structure is identical with the preferred form of valve structure shown in Figures 1 to 3 inclusive in all respects, excepting as to the construction of the packing follower. The stem 13' of the modified form of the valve structure carries the valve head 11' which cooperates with the valve seat 12'. The stem 13' extends outwardly through the valve attaching body 17' and has a threaded portion 18' formed thereon which threadably engages in the threaded bore 31 of the sleeve-like extension 32 of the packing follower 33. The packing follower 33 is bolted to the attaching body 17 and to the turbine casing 8' by attaching bolts 23'.

Instead of having a portion cut away to provide the yielding spring-like part of the packing follower as does the packing follower 21, the packing follower 33 of the modified form has a bellows-like structure 34 formed thereon between the main disc-like body 35 of the follower and the sleeve-like extension 32. This bellows-like structure 34 consists of a plurality of relatively thin radiating fin-like members, the adjacent ones of which are joined at both their inner and outer ends so as to form, in effect, a bellows as is clearly shown in Figure 4 of the drawings. This bellows-like structure being thinner than the remaining portions of the follower 33, provides a spring-like connection between the sleeve 32 and the body 35 of the follower 33 to permit yielding movement of the sleeve 32 under stress applied thereto by the expanding action of the threaded portion 18' of the stem 13', and thus prevent excessive binding of the threaded portion of the stem in the sleeve 32 and will permit the valve to be operated by hand at all times.

The sleeve-like extension 32 and the bellows-like structure 34 are, as is the sleeve-like extension 20, disposed outwardly of the outer face of the follower body 35 so that they are completely surrounded by atmosphere and are at the farthest point from the steam ring 4' of the turbine, and the bellows-like structure 34 will dissipate heat in the same manner or probably to a greater extent than will the fins 26. The chamber 36 which

surrounds a portion of the valve stem 13' is vented to atmosphere by a vent opening 37.

Figure 6 of the drawings shows a further modified form of the valve structure, wherein the valve stem 50 extends through and is threadably connected at 51 to the gland follower 52. The follower 52 compresses the packing 53 located in the bonnet 54. An annular spacer ring 55 is formed upon the gland follower 52 and engages or lies flat against the outer surface of the head 56 of the bonnet 54. The spacing ring 55 has holes 57 bored therethrough at spaced points.

A spring ring or element 58 rests upon the spacer ring 55, and is welded or otherwise attached to the gland follower 52 at the inner perimeter of the spring ring, so as to keep the spring ring from turning. The spring ring or element 58, the spacing ring 55, and the head 56 of the bonnet are attached to the turbine casting 59 by bolts 60.

The spring ring 55 will yield so as to accommodate, or compensate for expansion of the valve stem 50 and prevent binding of the threaded portion of the stem in the gland follower 52.

It will be understood that the invention is not to be limited to the specific construction or arrangement of parts shown, but that they may be widely modified within the invention defined by the claims.

What is claimed is:

1. In a valve, a housing, an attaching body attached to said housing, packing in said attaching body a packing follower attached to said housing and engaging said packing, a valve stem extending through said packing and movable in the follower and housing, an internally threaded sleeve extension formed on said follower, said valve stem having a threaded portion engaging in said threaded sleeve extension, said sleeve extension having a plurality of fins radiating from its outer surface to form heat dissipating means.

2. In a valve, a housing, an attaching body attached to said housing, packing in said attaching body a packing follower attached to said housing and engaging said packing, a valve stem extending through said packing and movable in the follower and housing, an internally threaded sleeve extension formed on said follower, said valve stem having a threaded portion engaging in said threaded sleeve extension, said sleeve extension having a plurality of fins radiating from its outer surface to form heat dissipating means, said follower having a relatively thin spring-like portion formed thereon which will yield under stress to prevent binding action of the valve stem in the threaded sleeve.

3. In a valve, a housing, an attaching body attached to said housing, packing in said attaching body a packing follower attached to said housing and engaging said packing, a valve stem extending through said packing and movable in the follower and housing, an internally threaded sleeve extension formed on said follower, said valve stem having a threaded portion engaging in said threaded sleeve extension, said sleeve extension having a plurality of fins radiating from its outer surface to form heat dissipating means, said fins being in the form of a bellows to form a spring-like portion of the follower which will yield under stress to prevent binding of the valve stem in the threaded sleeve extension.

4. In a valve, a housing, an attaching body attached to said housing, packing in said attaching body a packing follower attached to said

housing engaging said packing and having a sleeve-like extension formed thereon part of the bore of which extension is internally threaded, a valve stem extending through said packing and having a threaded portion engaging in the threaded portion of the sleeve-like extension, said follower being constructed of metal having some elasticity and embodying a relatively thin portion which will yield under stress to prevent binding of the valve stem and follower.

5. In a valve, a housing, a packing follower attached to said housing and having a sleeve-like extension formed thereon part of the bore of which extension is internally threaded, a valve stem having a threaded portion engaging in the threaded portion of the sleeve-like extension, said follower being constructed of metal having some elasticity and embodying a relatively thin portion which will yield under stress to prevent binding of the valve stem and follower, a portion of the bore of said sleeve-like extension being of larger diameter than the diameter of said valve stem to form a chamber, said follower having a vent opening therein venting said chamber to atmosphere.

6. In a valve, a housing, an attaching body attached to said housing, packing in said attaching body a packing follower attached to said housing engaging said packing and having a sleeve-like extension formed thereon part of the bore of which extension is internally threaded, a valve stem extending through said packing and having a threaded portion engaging in the threaded portion of the sleeve-like extension, said follower being constructed of metal having some elasticity and embodying a relatively thin portion which will yield under stress to prevent binding of the valve stem and follower, said sleeve-like extension having radiating extensions on its outer surface substantially in the form of heat dissipating ribs.

7. In a valve, a housing, a packing follower, a valve attaching-body, said follower having a flat surface for engagement with said attaching-body and having a sleeve-like extension formed thereon part of the bore of which is internally threaded, a valve stem having a threaded portion engaging in the threaded portion of the sleeve-like extension, a portion of said follower extending inwardly from said flat surface being cut away to form an annular recess and reduce the thickness of the follower to form a spring-like portion which will yield under stress to prevent binding of the valve stem and follower.

8. In a valve, a housing, a packing follower, a valve attaching-body, said follower having a flat surface for engagement with said attaching-body and having a sleeve-like extension formed thereon part of the bore of which is internally threaded, a valve stem having a threaded portion engaging in the threaded portion of the sleeve-like ex-

tension, a portion of said follower extending inwardly from said flat surface being cut away to form an annular recess and reduce the thickness of the follower to form a spring-like portion which will yield under stress to prevent binding of the valve stem and follower, said sleeve-like extension having a plurality of radiating extensions on its outer surface to form heat dissipating means.

10. 9. In a valve, a housing, a packing follower, a valve attaching-body, said follower having a flat surface for engagement with said attaching-body and having a sleeve-like extension formed thereon part of the bore of which is internally threaded, a valve stem having a threaded portion engaging in the threaded portion of the sleeve-like extension, a portion of said follower extending inwardly from said flat surface being cut away to form an annular recess and reduce the thickness of the follower to form a spring-like portion which will yield under stress to prevent binding of the valve stem and follower, said follower provided with a plurality of openings forming vents for the chamber formed by said annular recess.
15. 10. In a valve, a housing, a packing follower, a valve attaching-body, said follower having a flat surface for engagement with said attaching-body and having a sleeve-like extension formed thereon part of the bore of which is internally threaded, a valve stem having a threaded portion of the sleeve-like extension, a portion of said follower extending inwardly from said flat surface being cut away to form an annular recess and reduce the thickness of the follower to form a spring-like portion which will yield under stress to prevent binding of the valve stem and follower, said follower provided with a plurality of openings forming vents for the chamber formed by said annular recess, the unthreaded portion of the bore of said sleeve-like extension being greater
20. 25. 30. 35. 40. 45. in diameter than the diameter of the valve stem to form a leakage receiving chamber, said follower being provided with a vent opening therein opening into said chamber.
